SAFETY TRANSMISSION FOR VENDING
MACHINES AND THE LIKE

Otto Altman, Port Chester, N. Y.

Application September 20, 1946, Serial No. 698,276

5 Claims. (Cl. 74—470)

1

This invention relates to new and useful improvements in safety transmission mechanism for vending machines and the like.

More particularly, the invention proposes an elastic member connecting the depressible plunger or other similar element of a vending machine, or other type of machine, with a movable member which is movable at times and immovable at others. It is proposed to so construct the elastic member that it has sufficient stiffness to move the movable member when the latter is free to be moved, and to buckle when the movable member is immovable.

The new safety transmission is of great value in push button type of vending machines in which coins are deposited when purchases are made. In these machines persons often try to depress the plungers without depositing coins. Those designs of vending machines which have rigid connection are poor in that breakage must occur if the plungers are forced inwards unduly.

The invention specifically proposes to characterize the elastic member by the fact that it consists of a steel or other metal strip. It is proposed that this metal strip be arcuate in transverse cross section to stiffen it so that it has sufficient stiffness to transmit the motion and yet will buckle should the movable member be in an immovable condition. The invention also contemplates the association of guides with the elastic member for properly guiding it.

Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary front view of a vending machine constructed in accordance with this invention.

Fig. 2 is a fragmentary enlarged vertical sectional view taken on the line 2—2 of Fig. 1.

Fig. 3 is a fragmentary horizontal sectional view taken on the line 3—3 of Fig. 2.

Fig. 4 is a fragmentary enlarged detailed view of a portion of Fig. 2.

Fig. 5 is a fragmentary enlarged detailed view of a portion of Fig. 3.

2

Fig. 6 is a fragmentary enlarged vertical sectional view taken on the line 6—6 of Fig. 5.

Fig. 7 is a sectional view similar to Fig. 6 but illustrating the parts in a different position.

Fig. 8 is a fragmentary view similar to a portion of Fig. 2 but illustrating the parts in a different position.

The safety transmission for vending machines, and the like, in accordance with this invention, 10 has been shown associated with a vending machine having a casing 10 provided with a plunger holding portion 11 upon which a plurality of 15 depressible plungers 12 are mounted. A sign 14 is mounted upon the front of the casing portion 11 for indicating different merchandise which each plunger represents. A plurality of chutes 15 for holding stacks of the different articles A to be dispensed are mounted within the casing 10. Each chute 15 has a small opening 16 at its bottom 20 through which an injector may engage to push the bottom-most article A out of a back opening 17 so that it falls upon a discharge chute 18 and may be removed through a front opening 19 of the casing 10.

25 For each opening 16 there is an ejector 20 which is mounted on a horizontal plate 21 fixedly mounted in the casing 10. This plate 21 is provided with a slot 22 for each ejector 20. Each ejector 20 has rivets 23 and 24 engaging through 30 a slot 22 and connected with a slide block 25 slideable upon the bottom of the plate 21 by which the ejector 20 may be properly guided to move forwards to ejecting position, and rearwards.

35 Springs 26 are connected with the plungers 12 and with stationary support pins 27 and serve to normally urge the plungers 12 into their raised positions. Each plunger 12 is provided with a small stop block 29 which engages against a top stop wall 30 of the casing portion 11 and against 40 a bottom stop angle 31 mounted on casing 10 for limiting motion of each plunger 12.

Each ejector 20 is associated with a control member 32. Each control member 32 is pivotally mounted at its back end upon one of said rivets

45 23. The front ends of the control members 32 engage through openings 28 in the side wall of a channel-like member 34 which is mounted upon the bottom of the plate 21. This channel-like member 34 contains a plurality of adjacent contacting slides 35. The adjacent ends 36 of these slides 35 are beveled and the front ends of the control members 32 are pointed and adapted to fit in the spaces between the beveled ends 36. One end of the channel 34 is closed by a plate 37

50 mounted on a wall 40 fixed within casing 10. The

other end of the channel 34 is controlled by a lever 38. This lever 38 is pivotally supported by a pintle 39 upon one face of another wall 40 fixedly mounted within casing 10.

One end of the lever 38 is formed with a bevel 41 which is adapted to be engaged by a coin 42 passing through a coin chute 43 supported on one of the walls 40. The end 44 of the lever 38 is heavier than the other end of the lever so that the heavier end of the lever 38 normally tends to drop. A stop pin 45 limits the bottom position of this end of the lever, while another stop pin 46 limits the upward position of this end of the lever 38. These stop pins 45 and 46 are mounted on said wall 40. Said wall 40 has an opening 47 through which the end one of the slides 35 may project, providing that the lever 38 is not in the way. When the lever 38 is in a moved position, moved by the coin 42, it is free of the opening 47 so that the end side 35 is capable of passing under it. When the lever 38 is not moved by a coin it assumes the position shown in Fig. 7 and then the end slide 35 cannot move out. In Fig. 7 the end slide 35 and the opening 47 are schematically illustrated.

The end slide 35 is normally urged into a retracted position by a spring 48. This spring 48 acts between a stationary pin 49 mounted upon the bottom of the channel-like member 34 and a pin 50 mounted on the end slide 35 and projecting through a slot 51 formed in the bottom of the channel-like member 34.

Up to this point of the specification the vending machine is typical of any vending machine insofar as the movable ejectors 20, or we may call them movable members 20, cannot move forwards unless a coin 42 is in position at the bottom of the coin chute 43 and holds the lever 38 as shown in Fig. 6. In Fig. 3 one of the control members 32 is shown schematically in its forward position. In this position the slides 35 are moved so that the end slide 35 is extending past the lever 38.

The new safety transmission, in accordance with this invention, is connected between the plungers 12 and the movable members (ejectors) 20. The transmission for each plunger 12 includes an elastic member 54, such as a steel or other metal strip, connected between each plunger 12 and each movable member (ejector) 20. More specifically, each elastic member 54 is rigidly connected at its top end 55 to the plunger 12. The elastic member 54 extends downwards and then engages beneath a roller 56. A guide strip 57 also engages beneath each roller 56 and assists in guiding the bottom portions of the elastic members 54 horizontally. Each bottom horizontal portion of each elastic member 54 connects with a movable member (ejector) 20. The rivets 23 and 24 are also used for this connection. It should be noted that indirectly each elastic member 54 is connected with a control member 32 because it is connected with an ejector 20, which in turn is connected by a rivet 23 with the control member 32.

Each elastic member 54 is arcuate in transverse cross section so as to be stiffer. Each elastic member 54 must have sufficient stiffness so as to be capable of moving the movable member (ejector) 20 forwards when the plunger 12 is depressed. Each elastic member 54 is also capable of buckling, as for example illustrated in Fig. 8, when the plunger 12 is depressed and the movable member (ejector) 20 is in an immovable condition. The rollers 56 are mounted

on a shaft 60 which is supported across the plunger holding portion 11 of the casing 10.

The operation and use of the invention may be understood from the following:

Normally, the lever 38 extends across the end slide 35, as indicated in Fig. 7, so that the slides 35 are immovable. Now any one of the plungers 12 may be depressed. The elastic member 54 of the particular depressed plunger 12 will tend to move the ejector 20 forwards, but because the control member 32 is incapable of prying apart a pair of adjacent slides 35 because the end slide 35 is held by the lever 38, the movable member (ejector) 20 is immovable and the elastic member 54 will buckle, as illustrated in Fig. 8. Because the elastic member 54 merely buckles no damage will be done to any of the operating parts of the vending machine. When the plunger 12 is released it will be returned to its raised position by the spring 26, and the elastic member 54 will assume its original upright position as shown in Fig. 2.

When a coin is dropped in the coin chute of the vending machine it will engage the lever 38, moving the lever 38 to the position shown in Fig. 6, so as to free the end slide 35. Now the slides 35 are free to move, which in turn indirectly frees all of the movable members 20. Now any one of the plungers 12 may be depressed. This motion will be transmitted by one of the elastic members 54 to one of the ejectors 20 which will move forward and engage into the bottom of one of the chutes 15 and discharge the bottom-most article A through the opening 17 so that it falls upon the chute 18 and may be removed through the opening 19. When this ejector 20 moves forwards, its control member 32 spreads apart adjacent slides 35 so that the end slide 35 projects through the opening 47 as illustrated in Fig. 5. Should this plunger 12 be held down it will be possible to depress another one of the plungers 12 but its elastic member 54 will merely buckle because now the slides 35 are incapable of moving further. The pin 50 of the end slide 35 is limited by the slot 51. When the plunger 12 is released the coin 42 will be discharged from the lever 38 by the usual mechanism, not illustrated on the drawing.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A safety transmission for vending machines and the like, comprising a movable member, means for holding said member substantially immovable at times, a depressible plunger, and an elastic member connecting said plunger and movable member and having sufficient stiffness to move said movable member when said plunger is depressed and having a portion extending substantially in the direction of motion of said plunger and adapted to buckle when said movable member is immovable and said plunger is depressed.

2. A safety transmission for vending machines and the like, comprising a movable member, means for holding said member substantially immovable at times, a depressible plunger, and an elastic member connecting said plunger and mov-

able member and having sufficient stiffness to move said movable member when said plunger is depressed and adapted to buckle when said movable member is immovable and said plunger is depressed, said elastic member comprising a metal strip of arcuate shape in transverse cross section for stiffening purposes.

3. A safety transmission for vending machines and the like, comprising a movable member, means for holding said member substantially immovable at times, a depressible plunger, and an elastic member connecting said plunger and movable member and having sufficient stiffness to move said movable member when said plunger is depressed and adapted to buckle when said movable member is immovable and said plunger is depressed, said elastic member comprising a metal strip of arcuate shape in transverse cross section for stiffening purposes, and guides for directing said metal strip.

4. A safety transmission for vending machines and the like, comprising a movable member, means for holding said member substantially immovable at times, a depressible plunger, and an elastic member connecting said plunger and movable member and having sufficient stiffness to move said movable member when said plunger is depressed and adapted to buckle when said movable member is immovable and said plunger is depressed, said elastic member comprising a metal strip of arcuate shape in transverse cross section

for stiffening purposes, and guides for directing said metal strip, including a roller beneath which said metal strip passes.

5. A safety transmission for vending machines and the like, comprising a movable member, means for holding said member substantially immovable at times, a depressible plunger, and an elastic member connecting said plunger and movable member and having sufficient stiffness to move said movable member when said plunger is depressed and adapted to buckle when said movable member is immovable and said plunger is depressed, said elastic member comprising a metal strip of arcuate shape in transverse cross section for stiffening purposes, and guides for directing said metal strip, including a roller beneath which said metal strip passes, and a guide strip engaging said metal strip and holding it against the curvature of said roller.
